UNITED STATES PATENT OFFICE.

CHARLES F. BENNETT, OF CHICAGO, ILLINOIS.

COMBINED JOCK-STRAP AND SUSPENSORY.

SPECIFICATION forming part of Letters Patent No. 594,673, dated November 30, 1897.

Application filed March 29, 1897. Serial No. 629,828. (No model.)

To all whom it may concern:

Be it known that I, CHARLES F. BENNETT, a citizen of the United States, residing at Chicago, in the county of Cook and State of Illinois, have invented a new and useful Improvement in a Combined Jock-Strap and Suspensory, of which the following is a specification.

The object of my invention is to provide, 10 as a new article of manufacture, a jock-strap which shall be formed entire in one piece—that is, without separated parts that require, for adjusting the device on the person—to be fastened, as by means of buckles and straps, 15 or by lacing and the like, and which is composed throughout, by preference, at least, of elastic fabric and with a suspensory as an integral part of the structure.

Referring to the accompanying drawings, 20 Figure 1 is a perspective view of my improved combined jock-strap and suspensory, and Fig. 2 a section taken at the line 2 on Fig. 1 and viewed in the direction of the arrow.

The device may be woven or knitted entire 25 and thereby formed with my improvements, or it may, as in the case of that from which the drawings herein were made, be cut out of the proper elastic fabric to afford the waist portion A, the ends of which are permanently 30 sewed or otherwise joined together to render it endless, and the flaps B and C, depending

from the front of the waist portion, crossed one upon the other, as shown at *x*, and there fastened together, as by stitching, and the ends are fastened to the back of the waist 35 portion to afford the thigh-circlets B' and C'. In crossing the flaps B and C, or provided otherwise if the device is produced in the other way suggested, the fold is caused to form a sack D, affording a suspensory. 40

My improved device is especially intended for the use of riders, more particularly bicycle-riders, though it is useful for all purposes in which it is customary to wear a jock-strap. 45

What I claim as new, and desire to secure by Letters Patent, is—

A combined jock-strap and suspensory comprising an endless belt portion, and two elastic bands separated at one end and attached 50 to the rear of the belt and crossed intermediate of their length and secured together at their inner edges from said point of crossing to the other end and attached at said other end to the front of the belt, whereby there is 55 provided at the rear an opening and at the front a pouch, substantially as and for the purpose set forth.

CHARLES F. BENNETT.

In presence of—

J. H. LEE,

R. T. SPENCER.
